RAILWAY TRAFFIC CONTROLLING APPARATUS

Filed Oct. 18, 1929

UNITED STATES PATENT OFFICE

LESTER E. SPRAY, OF WILKINSBURG, PENNSYLVANIA, ASSIGNOR TO THE UNION SWITCH & SIGNAL COMPANY, OF SWISSVALE, PENNSYLVANIA, A CORPORATION OF PENNSYLVANIA

RAILWAY-TRAFFIC-CONTROLLING APPARATUS

Application filed October 18, 1929. Serial No. 400,555.

My invention relates to railway traffic controlling apparatus, and particularly to apparatus for controlling traffic governing devices, such as railway track switches, by levers which are grouped together in a central location such as an interlocking tower.

One feature of my invention is the provision of means for at times controlling in multiple, by current from a normal source, an electric lock and an indication means associated with each of these levers, and for at times controlling the electric lock only by current from an emergency source.

I will describe one form of apparatus embodying my invention, and will then point out the novel features thereof in claims.

The accompanying drawing is a diagrammatic view showing one form of railway traffic controlling apparatus embodying my invention.

Referring to the drawing, the reference characters 1, 1^a, 1^b, 1^c, 1^d and 1^e designate the track rails of tracks X, Y and Z, respectively, in a railway switching or interlocking plant. By means of a switch F¹, track X is connected with a siding. By means of switch F², track X is connected with a crossover which is, in turn, connected with track Y by means of switch F^{2a}. Tracks Y and Z are similarly interconnected by switches F³ and F^{3a} and an intervening crossover track.

By means of insulated joints 2, a section A-B is insulated from adjoining portions of track X. Also, by means of other insulated joints 2, two sections C-D and D-E are insulated from each other and from adjacent portions of track Y. A section G-H is similarly insulated from adjacent portions of track Z by means of other insulated joints 2.

Each of these sections is supplied with current by a track transformer 3, connected across the rails adjacent one end of the section, and is provided with a track relay designated by the reference character R with a distinguishing exponent and connected across the rails adjacent the opposite end of the section. The primary winding of each transformer 3 is constantly supplied with current by wires α and β from a source not shown in the drawing.

The operation of switch F¹ is controlled by a manually operable lever V¹; the operation of switches F² and F^{2a} is controlled by a manually operable lever V²; and the operation of switches F³ and F^{3a} is controlled by a manually operable lever V³. Each of these levers has a normal position *n*, a normal track circuit locking or detector locking position *f*, a normal indication locking position *b*, a reverse indication locking position *d*, a reverse detector locking position *t*, and a full reverse position *r*. Each of these levers operates four contacts, 7, 8, 9 and 10. Each contact 7 is closed while its lever is in its *r* or *t* or any intermediate position; each contact 8 is closed while its lever is in the *n* or *f* or any intermediate position; each contact 9 is closed while its lever is in its *b* position only; and each contact 10 is closed while its lever is in the *d* position only.

The manual operation of each of these levers is controlled by two electric lock magnets designated by the reference character L with distinguishing exponents. Each magnet L, when energized, attracts a dog 4, and when deenergized, permits its dog 4 to drop against a segment 5 or 6, respectively, which is operated by its lever. As shown in the drawing, magnets L¹, L² and L³ are energized, and hence the dog 4 for each of these magnets is lifted away from its segment 5. Magnets L^{1a}, L^{2a} and L^{3a} are de-energized, as shown in the drawing, and hence the dog 4 for each of these magnets is down against its segment 6.

With the levers in the *n* position, as shown in the drawing, segments 5 and 6 are held toward the right by their levers. When any one of these levers is moved towards its *r* position, each of its segments 5 and 6 is moved toward the left along an arc of a circle. Each segment 5 is provided with a stop 53. If, when the associated magnet L is de-energized, an attempt is made to move the lever toward the *r* position, stop 53 of the segment 5 engages the associated dog 4, when the lever reaches the *f* position, and prevents further movement of the lever until the magnet is energized. If, after the lever is moved past its *f* position, the magnet associated with

its segment 6 continues de-energized, a stop 54, with which segment 6 is provided, engages its dog 4 when the lever reaches the *d* position. Further movement of the lever toward the *r* position is now prevented until the magnet associated with segment 6 becomes energized. The movement of each lever from its *r* position toward its *n* position may be similarly arrested at positions *t* and *b*.

Indicators, here shown as electric lamps e^1 , e^2 and e^3 , are associated with levers V^1 , V^2 and V^3 , respectively. These indicators inform the leverman when the levers can be moved from their *n* or *r* positions past the *f* or *t* positions, respectively.

Asymmetric units designated N^1 , N^2 and N^3 , respectively, permit current to flow in one direction only through lamps e and the magnets L .

A power-off relay, designated by the letter W , is constantly energized by current from wires x and o except in the event of a failure of the source which supplies current to wires x and o .

Magnets L and indicator lamps e are normally supplied with current from a rectifier T which is constantly connected to wires x and o . In case of a failure of the normal source which supplies current to wires x and o , magnets L but not lamps e can be energized by current from an emergency source here shown as a battery Q . Selection between rectifier T and battery Q is effected by relay W in conjunction with a manually operable device here shown as a master lever V^4 .

Master lever V^4 has a normal position *n* and a reverse position *r*. Lever V^4 operates eleven contacts. Of these, contacts 11, 39, 36, 32, 28 and 25 are closed when lever V^4 is in its *n* position, and contacts 52, 45, 47, 49 and 50 are closed when lever V^4 is in its *r* position.

Rectifier T , as here shown, comprises asymmetric units N^4 , N^5 , N^6 and N^7 . Each of these units and units N^1 , N^2 and N^3 may be similar to those described and claimed in Letters Patent of the United States, No. 1,640,335, granted to L. O. Grondahl, August 23, 1927.

A polarized switch indication relay K^1 is so controlled by switch F^1 as to be energized in a normal direction when switch F^1 is in its normal position, and to be energized in the reverse direction when switch F^1 is in its reverse position. A similar polarized switch indication relay K^2 is energized in the normal direction when switches F^2 and F^2_a are in their normal position, and is energized in the reverse direction when these switches are in their reverse position. Relay K^3 is similarly controlled by switches F^3 and F^3_a .

Circuits for controlling the different switches by levers V^1 , V^2 and V^3 , respectively, and the circuits for controlling relays K^1 ,

K^2 and K^3 by these switches are well known and form no part of my present invention, and are hence omitted from the drawing.

Having thus described, in general, the arrangement and location of the various parts comprising my invention, I will now trace the operation of the apparatus.

As shown in the drawing, all parts are in their normal condition, that is, each switch F is in its normal position for traffic moves along the main tracks X , Y and Z only; each track section is unoccupied; each lever V is in its *n* position; and relay W is energized by current from wires x and o . The track sections being unoccupied, relays R^1 , R^2 , R^3 and R^4 are energized.

Under these conditions, magnet L^1 is energized by its circuit passing from rectifier T , through contact 11 of lever V^4 , contact 12 of relay W , wire 16, contact 17 of relay R^1 , wires 20 and 21, contact 8 of lever V^1 , winding of magnet L^1 , asymmetric unit N^1 , wire 24, contact 25 of lever V^4 , and wire 26 back to rectifier T . Lamp e^1 is lighted by current flowing from rectifier T over the path just traced as far as wire 20, thence through wire 27, contact 28 of lever V^4 , wire 29, lamp e^1 , and wire 30 to unit N^1 . Magnet L^2 is energized by its circuit which includes the circuit already traced for magnet L^1 as far as contact 17 of relay R^1 , thence through contact 18 of relay R^2 , wire 19, contact 8 of lever V^2 , winding of magnet L^2 , asymmetric unit N^2 , and wire 22 to wire 24. Lamp e^2 is lighted by current flowing in the circuit just traced for magnet L^2 except passing from contact 18 of relay R^2 , through wire 31, contact 32 of lever V^4 , wire 33, lamp e^2 , and wire 34 to unit N^2 .

Magnet L^3 is energized by its circuit which passes from rectifier T , through contact 11 of lever V^4 , contact 12 of relay W , contact 13 of relay R^4 , contact 14 of relay R^3 , wire 15, contact 8 of lever V^3 , winding of magnet L^3 , asymmetric unit N^3 , wires 23, 22 and 24, contact 25 of lever V^4 , and wire 26 back to rectifier T . Lamp e^3 is lighted by current flowing in a circuit which follows the path just traced for the circuit for magnet L^3 as far as contact 14 of relay R^3 , thence through wire 35, contact 36 of lever V^4 , wire 37, lamp e^3 , and wire 38 to unit N^3 .

Since all switches are in their normal position, all relays K are energized in the normal direction.

I will assume that the leverman desires to reverse switch F^1 for a traffic movement from the siding to track X . He therefore moves lever V^1 toward its *r* position. Magnet L^1 being energized, lever V^1 passes its *f* position but is arrested at its *d* position by engagement of stop 54 of segment 6 with dog 4 of magnet L^1 . With lever V^1 in its *d* position, the reverse operating circuit for switch F^1 becomes closed, and switch F^1 is then moved to its reverse position, causing

relay K^1 to be energized in the reverse direction. Magnet L^1_a thereupon becomes energized by its circuit passing from rectifier T, through contact 39 of lever V^4 , contact 40^a of relay W, wire 41, contacts 42 and 43^b of relay K^1 , contact 10 of lever V^1 , winding of magnet L^1_a , asymmetric unit N^1 , wire 24, contact 25 of lever V^4 , and wire 26 back to rectifier T. Magnet L^1_a , being thus energized, lifts its dog 4 out of engagement with stop 54, and the leverman then continues the operation of lever V^1 to its r position.

I will also assume that when the train has passed out of the siding and on through section A—B, the leverman starts to return lever V^1 to its normal position, but finds that the source which supplies current to wires ω and σ has failed, and that hence relay W is de-energized. Magnet L^1_a has a second circuit which is exactly similar to the circuit already traced for magnet L^1 except that it includes contact 7 instead of contact 8 of lever V^1 . With relay W de-energized, this circuit is open at contact 12 of relay W, and hence the movement of lever V^1 is arrested at its t position by engagement of stop 54 of segment 6 with dog 4 of magnet L^1_a . On account of contact 12 of relay W being open, lamp e^1 is unlighted.

In order to return lever V^1 to its normal position, the normal source of power having failed, the leverman moves lever V^4 to its r position. Magnet L^1_a is now energized by a third circuit passing from battery Q, through contact 44 of relay W, wires 46 and 48, contact 49 of lever V^4 , wires 27 and 21, contact 7 of lever V^1 , winding of magnet L^1_a , unit N^1 , wire 24, and contact 50 of lever V^4 back to battery Q. The circuit for lamp e^1 is open at contact 28 of lever V^4 , and hence lamp e^1 continues unlighted. The leverman now continues the movement of lever V^1 to its b position at which its further movement is arrested by stop 53 of segment 5 engaging its dog 4. With lever V^1 in its b position, the normal operating circuit for switch F^1 returns switch F^1 to its normal position, causing relay K^1 to again be energized in the normal direction. A second circuit is now completed for magnet L^1 passing from battery Q, through contact 52 of lever V^4 , contact 40^b of relay W, wire 41, contacts 42 and 43^a of relay K^1 , contact 9 of lever V^1 , winding of magnet L^1 , unit N^1 , wire 24, and contact 50 of lever V^4 back to battery Q.

I will next assume that with all parts again in their normal condition as previously described, except with relay R^1 de-energized, the leverman attempts to again reverse switch F^1 . Since relay R^1 is de-energized, the circuit first traced for magnet L^1 is open at contact 17 of relay R^1 , and hence magnet L^1 is de-energized. Lever V^1 is therefore arrested at its position f by stop 53 engaging dog 4.

If now the leverman attempts to release lever V^1 by means of lever V^4 , he cannot do so, since the emergency circuit for magnet L^1 , which is exactly similar to the third circuit previously traced for magnet L^1_a except that it includes contact 8 instead of contact 7 of lever V^1 , is open at contact 44 of relay W.

From the foregoing examples of operation of the apparatus, it follows that before emergency source Q can supply current to any part of the apparatus, relay W must be de-energized and lever V^4 must be moved to its r position. The lighting circuit for each lamp e comprises a contact which is operated by lever V^4 and which is closed when lever V^4 is in its n position only. This contact is opened when lever V^4 is moved to its r position, and hence emergency battery Q cannot at any time supply current to any of the lamps e .

I will not assume that with all parts again in their normal condition as previously described, wire 22 between unit N^1 and unit N^2 becomes disconnected or broken. If now a train enters section A—B, opening the circuit first traced for magnet L^1 by dropping contact 17 of relay R^1 , current could be supplied to magnet L^1 through lamps e^2 and e^3 in multiple with magnets L^2 and L^3 , respectively, if asymmetric unit N^2 were not present. The circuit by which this could be done would pass from rectifier T, through contact 11 of lever V^4 , contact 12 of relay W, contact 13 of relay R^4 , contact 14 of relay R^3 , wire 15, contact 8 of lever V^3 , winding of magnet L^3 , asymmetric unit N^3 , wire 23, winding of magnet L^2 , contact 8 of lever V^2 , wire 19, contact 18 of relay R^2 , wires 20 and 21, contact 8 of lever V^1 , winding of magnet L^1 , unit N^1 , wire 24, contact 25 of lever V^4 , and wire 26 back to rectifier T. This circuit would have a branch path around magnet L^3 , through lamp e^3 as already traced, and would have a second branch path around magnet L^2 , through lamp e^2 as already traced. Magnets L^1 , L^2 and L^3 might thus be sufficiently energized to attract or retain their dogs 4 away from their stops 53, whereas, with unit N^2 in the circuit, as shown in the drawing, magnets L^1 , L^2 and L^3 would all be de-energized in the event of a break in wire 22 and the de-energization of relay R^1 .

I will next assume that, through an error, wire 26 has been connected to terminal 55 of rectifier T, and that terminal 56 of rectifier T is connected with contacts 11 and 39 of lever V^4 instead of as shown in the drawing. If, at the same time, terminal 56 of rectifier T and contact 8 of lever V^1 were grounded, then, if it were not for unit N^1 , magnet L^1 could be energized although relay R^1 were de-energized. The circuit for this would pass from terminal 55 of rectifier T, through wire 26, contact 25 of lever V^4 , wire 24, winding of

magnet L¹, contact 8 of lever V¹, and ground back to terminal 56 of rectifier T.

From the foregoing description and the accompanying drawing, it is clear that my invention provides means for controlling in multiple from a normal source a lock and an indication means associated with a lever for controlling a railway traffic governing device, and for controlling only the lock from an emergency source when the normal source fails. It is clear that my invention also provides means for protecting against false operation of the lock by current of reverse polarity from the normal source.

Although I have herein shown and described only one form of railway traffic controlling apparatus embodying my invention, it is understood that various changes and modifications may be made therein within the scope of the appended claims without departing from the spirit and scope of my invention.

Having thus described my invention, what I claim is:

1. In combination, a manually operable lever for controlling a railway track switch, an electric lock, means controlled by said electric lock for preventing operation of said lever when said electric lock is de-energized, an indication means, a second manually operable lever having a normal and a reverse position, a source of current, a second source of current, means controlled by said second lever for energizing both said electric lock and said indication means by current from said first source when said second lever is in its normal position, and means controlled by said second lever for energizing said electric lock but not said indication means by current from said second source when said second lever is in its reverse position.

2. In combination, a manually operable lever for controlling a railway track switch, an electric lock, means controlled by said electric lock for preventing operation of said lever when said electric lock is de-energized, an indication means, a source of current, a relay energized by current from said source, a second source of current, a circuit including said electric lock and said indication means connected in multiple, means controlled by said relay for transmitting energy from said first source to said circuit, and means controlled by said relay for transmitting energy from said second source to said electric lock but not to said indication means when said first source fails.

3. In combination, a manually operable lever for controlling a railway track switch, a control circuit, a second control circuit, a source of current, a second source of current, a manually operable device having a normal and a reverse position, means controlled by said manually operable device for supplying said first control circuit with current from

said first source when said manually operable device is in its normal position, means controlled by said manually operable device for supplying said second control circuit with current from said second source when said manually operable device is in its reverse position, means controlled by either said first or said second control circuit for controlling said lever, and an indication means controlled by said first control circuit but not by said second control circuit.

4. In combination, a manually operable lever for controlling a railway track switch, a control circuit, a second control circuit, a source of current, a second source of current, a manually operable device having a normal and a reverse position, means controlled by said manually operable device for supplying said first control circuit with current from said first source when said manually operable device is in its normal position, means controlled by said manually operable device for supplying said second control circuit with current from said second source when said manually operable device is in its reverse position, means controlled by either said first or said second circuit for controlling said lever, an indication means controlled by said first control circuit, and means controlled by said manually operable device for preventing said second control circuit from controlling said indication means.

5. In combination, a manually operable lever for controlling a railway track switch, an indication means, a manually operable device having a normal and a reverse position, means controlled by said device for controlling said lever and said indication means when said device is in its normal position, and means controlled by said device for controlling said lever but not said indication means when said device is in its reverse position.

6. In combination, a manually operable lever for controlling a railway track switch, an indication means, a source of current, a relay energized by current from said source, a second source of current, means controlled by said relay for controlling said lever and said indication means by current from said first source, and means controlled by said relay for controlling said lever but not said indication means by current from said second source when said first source has failed.

7. In combination, a manually operable lever for controlling a railway track switch, an electric lock, means controlled by said electric lock for preventing operation of said lever when said electric lock is de-energized, an indication means, a source of current, a second source of current, a manually operable device, means controlled by said device for at times energizing said electric lock and said indication means in multiple by current from said first source, means controlled by said

device for at times energizing said electric lock by current from said second source, and means controlled by said device for preventing current from said second source from reaching said indication means.

8. In combination, a manually operable lever for controlling a railway track switch, an electric lock, means controlled by said electric lock for preventing operation of said lever when said electric lock is de-energized, an indication means, a source of current, a relay energized by current from said source, a manually operable master lever having a normal contact which is closed when said master lever is in a normal position and a reverse contact which is closed when said master lever is in a reverse position, a control circuit for said electric lock and said indication means including said normal contact and a front contact of said relay and supplied with current from said source, a second source of current, and a second control circuit for said electric lock including said reverse contact and a back contact of said relay and supplied with current from said second source.

9. In combination, control means for a railway track switch, an indication means, a source of alternating current, a source of direct current, a manually operable device, means controlled by said device for at times controlling said control means and said indication means by current from said alternating current source, and means controlled by said device for at times controlling said control means but not said indication means by current from said direct current source.

10. In combination, a plurality of manually operable levers for controlling the operation of a plurality of railway track switches, an indication means for each of said levers, a source of current, a second source of current, a manually operable device, means controlled by said device for at times controlling the operation of each of said levers and its indication means by current from said first source, and means controlled by said device for at times controlling each of said levers but not its indication means by current from said second source.

11. In combination, a plurality of control means for a plurality of railway track switches, a manually operable device, means controlled by said device for energizing each of said control means by current of normal polarity from a common source, and means comprising asymmetric units for preventing current of reverse polarity from reaching any of said control means.

12. In combination, a plurality of manually operable levers each of which controls the operation of one of a plurality of railway track switches respectively, a manually operable device, means controlled by said device for controlling the operation of each of said levers by current of normal polarity from a

common source, an asymmetric unit for each of said levers, and means comprising each of said asymmetric units for preventing current of reverse polarity from controlling its lever.

13. In combination, a plurality of manually operable levers each of which controls the operation of one of a plurality of railway track switches respectively, a manually operable device, means controlled by said device for controlling in multiple the operation of said levers, and means including asymmetric units for preventing control of any one of said levers in series with any other said lever.

In testimony whereof I affix my signature.
